CLAIM

An ornamental design for a laser processing machine, as shown.

DESCRIPTION

FIG. 1 is a front elevational view of a laser processing machine showing our new design;

FIG. 2 is a top plan view;

FIG. 3 is a bottom plan view;

FIG. 4 is a top, rear and left side perspective view;

FIG. 5 is a top, rear and left side perspective view, shown with the control consul in an alternate condition of use;

FIG. 6 is a left side elevational view;

FIG. 7 is a right side elevational view; and,

FIG. 8 is a rear elevational view thereof.

FIGS. 4 and 5 have been drawn on an enlarged scale with respect to FIGS. 1-3 and 6-8.

FIG.1

FIG.2

FIG.3

FIG. 6

FIG. 7

FIG. 8
